Wilford, EnglandApplication December 19, 1945, Serial No. 635,903
In Great Britain July 31, 1944

5 Claims. (Cl. 66—109)

1

This invention relates to improvements in straight-bar knitting machines and refers particularly to improvements in machines of this kind used for knitting the heel tabs of stockings formed with French feet. In making stockings with French feet the usual method is to knit a blank comprising the leg, instep and sole portion of the stocking and this blank is then run onto the needles of a machine specially adapted to knit the heel tabs onto the appropriate part of the blank. Machines for this purpose are provided with two groups of needles spaced the requisite distance apart and each group is provided with the usual jack and dividing sinkers and knocking-over bits. The blank is then run onto the needles for the knitting of the heel tabs whilst the needle bar is withdrawn from the sinkers and as this operation is carried out by hand the needles may be bent, unless great care is used, so that they do not register with the transfer points when these are subsequently brought into operation. Furthermore the blank when run on the needle has a tendency to pull the needles at the sides of each group inwards so that they foul the sinkers when returned to their normal operative positions. In machines for knitting heel tabs as hitherto constructed the knocking-over bits are carried from one end and as they are of necessity very thin they can give practically no support to the needles to prevent them being displaced from their normal position.

The object of the present invention is to provide additional support to the knocking-over bits so that they can prevent the needles being displaced from their normal positions and also prevent displacement of the knocking-over bits during the knocking-over operation.

According to this invention the knocking-over bits are secured at one end in the knocking-over bar in the usual manner and have their other ends supported in tricks in a bar which is preferably carried so as to move with the knocking-over bar. Provision is made for separating the two bars so that access can be had to the needle-bar in order that damaged needles can be replaced.

The invention will now be more particularly described with reference to the accompanying drawings in which—

Fig. 1 is an end elevation of part of a straight-bar knitting machine showing the needle bar and associated knocking-over bits supported at both ends, being secured in a bar at the rear of

2

the needles and engaging in tricks in a bar disposed at the front of the needles.

Fig. 2 is a plan of the knocking-over bits and their supporting bars shown detached.

Fig. 3 is a sectional side elevation on the line XX of Fig. 2.

Fig. 4 is a sectional side elevation of an alternative construction showing the knocking-over bits secured in a bar at the front of the needles and engaging in tricks in a bar disposed at the rear of the needles.

Like letters indicate like parts throughout the drawings.

In one method of carrying out this invention as shown in Fig. 1 the knocking-over bits A are mounted in the usual manner in the knocking-over bar B which is disposed at the back of the needle-bar C and is carried by the usual arms D and operated to provide the necessary movement to the knocking-over bits in well known manner. Disposed on the opposite side of the needle-bar C to the knocking-over bar B, that is at the front of the needles is a second bar E. This second bar E is disposed at approximately the same level as the knocking-over bar B and is provided with tricks therein to receive the ends of the knocking-over bits A as clearly shown in Fig. 2. This second bar E is preferably mounted so that it has a motion corresponding to that of the knocking-over bar B so that wear between the knocking-over bits and the tricks is obviated. For this purpose the second bar E may conveniently be carried by arms F which are attached to the knocking-over bar arms D so as to move therewith. For this purpose the lower ends of the arms F are connected at G to extensions D¹ on the lower end of the arms D.

It will be understood that with this arrangement the knocking-over bits A are supported on both sides of the needles C¹ and that provision must be made for separating the two bars B, E, associated with the knocking-over bits A in order that access can be obtained to the needle-bar C for the changing of needles C¹. Provision for separating the two bars B, E, can be conveniently arranged by pivoting the arms F which carry the second or tricked bar E to the arms D which carry the knocking-over bar B and interconnecting the bars or the arms which carry them by straps adapted to hold the two bars in their operative positions relatively to each other. Provision is made for quickly releasing the straps so that the two bars can be separated to give access to the needle-bar when required. Alternatively a catch H is pivoted on the bar E and

engages with a pin J carried by the knocking-over bar B. A spring K is provided to hold the catch H in engagement with the pin J.

When the knocking-over bar B' is disposed at the front of the needle bar C as shown in Fig. 4 5 the rear end of the knocking-over bits A' engage in tricks in a bar E' disposed at the rear of the needles. The knocking-over bar B' is provided with arms D' as in the previously described arrangement and the lower ends of the arms D' are pivoted at L' to the lower ends of the arms F' provided on the bar E'. The bars B' and E' are connected together in a similar manner to that described in connection with the previous arrangement and shown in Figs. 1 to 3 of the drawings except that the catch H' urged by the spring K' is pivoted on the knocking-over bar B' and engages with a pin J' carried by the bar E'.

The bar E' is preferably made integral with the arms F' and the tricks cut in sections secured thereto as shown in the drawings.

It will be apparent by reference to Figure 1 that in order to provide the knitting motion to the knocking-over bits, the knocking-over bar and its associated tricked bar are carried by the ends of arms M secured on a shaft N which is angularly adjusted in well known manner by a cam on the mainshaft O of the machine to provide the up and down motion to the knocking-over bits A. The in and out motion of the latter is obtained by a link P which is connected between an arm Q on the knocking-over bar B and one arm of a bell crank lever R, the other arm of which is provided with a truck engaging with a cam on the mainshaft O. It will be seen that with the knocking over bits supported on both sides of the needles they must be moved forward with the needles when the latter are moved clear to the sinkers for the work to be run onto them. The needle bar is moved forward in well known manner by adjusting the position of the presser arm S and in order to permit of the knocking-over bits moving forward at the same time the following arrangement is adapted. The link P is formed with a slot at the end connected to the lever R and this slot engages with a pin T on the lever R. The presser arm S is formed with a swell S¹ thereon which is adapted to engage with a pin P¹ on the link P when the presser arm S is adjusted and disengage the link P from the pin so that the knocking over bits are free to move forward with the needles. The link P will automatically re-engage with the pin when the needles are restored to their operative position. A spring may be provided in connection with the link P to hold it in engagement with the pin T when the needles are in their normal operative position.

With the arrangement described the knocking-over bits are stiffened against lateral movement and consequently can support the needles during the running on operation to prevent them being displaced. Additional support is also provided for the knocking-over bits during the knocking-over operation, and this additional support is particularly advantageous where the knocking-over bar is disposed to the front of the needle-bar.

What we claim as our invention is:

1. A straight-bar knitting machine in which the knocking-over bits are secured at one end in a bar and have their other ends supported in tricks in a second bar supported by arms the ends of which are pivoted to arms secured to the first bar and held in its operative position relatively to the latter by a disengageable connection.

2. A straight-bar knitting machine having in combination needles, sinkers, knocking-over bits secured at one end in a bar disposed on one side of the needles, arms on the bar, a second bar disposed on the other side of the needles, tricks in the second bar to receive the other ends of the knocking-over bits, arms on the second bar pivoted to the arms on the other bar, and a catch on one bar to engage with a pin on the other bar to hold the two bars in operative relationship.

3. A straight bar knitting machine according to claim 2 in which the catch is pivoted on one bar and is held in engagement with the pin on the other bar by a spring.

4. A straight bar knitting machine according to claim 2 in which the tricked bar is disposed in the front of the needles and the knocking-over bits are secured in a bar disposed at the rear of the needles.

5. A straight-bar knitting machine according to claim 2 in which the knocking-over bits have one end secured in a bar disposed at the front of the needles and have their other ends engaging in tricks in a bar disposed at the back of the needles.
